(57) **CLAIM**

The ornamental design for a display device with graphical user interface, as shown and described.

DESCRIPTION

FIG. 1 is a front view of a first image in the sequence for a display device with graphical user interface, showing our new design;

FIG. 2 is a front view of a second image thereof; and,
FIG. 3 is a front view of a third image thereof.

The broken lines in the figures showing a display screen, electronic device, and portions of the graphical user interface are for illustrative purposes only and form no part of the claimed design.

The appearance of the transitional image sequentially transitions between images shown in FIGS. 1 through 3. The process or period in which one image transitions to another image forms no part of the claimed design.
